UNITED STATES PATENT OFFICE.

JOHN HARRIS, OF SHEFFIELD, ENGLAND, AND DAVID HIBBERT THOMAS, OF MORRISTON, WALES.

EVAPORATOR.

1,203,614.

Specification of Letters Patent.

Patented Nov. 7, 1916.

Application filed November 29, 1915. Serial No. 64,074.

To all whom it may concern:

Be it known that we, JOHN HARRIS and DAVID HIBBERT THOMAS, subjects of the King of England, and residents, respectively, 5 of Sheffield, England, and Morriston, Wales, have invented certain new and useful Improvements in Evaporators, of which the following is a specification.

This invention relates to an evaporator 10 for acid, alkaline or neutral liquors, syrup or the like of the kind in which pipe-like evaporating vessels extend across a heating flue and through its walls, the object of the invention being to provide improvements in 15 the construction, arrangement and operation thereof. The pipe-like vessels have sometimes been arranged side by side with a packing of refractory material between them so that their bases form the roof of the flue, 20 and sometimes they have been separated to enable the heating gases to play all around them, but according to the present invention a combination of these dispositions is employed; that is to say the pipe-like vessels 25 are arranged side by side in two or more rows to form preferably horizontal baffles with ports at alternate ends so that the flue gases first pass along the bases of the lower-most row, thence to their upper portions and 30 the lower parts of the row above and so on to the chimney. The liquor to be concentrated is fed separately to each vessel in the top row, whence it flows successively to the corresponding vessel in each row below, 35 until it reaches a common discharge channel, so that the concentration is divided into a number of separate processes carried on simultaneously and corresponding to the number of vessels in each row.

40 The present invention also comprises improvements in the construction of the pipe-like vessels hereinafter more particularly detailed.

In the accompanying drawings:—Figure 45 1 is a sectional elevation and Fig. 2 a transverse section of apparatus according to this invention.

A is the fireplace and B the heating flue across which the pipe-like evaporating vessels C extend, the vessels being arranged side by side as shown in two or more rows so as to form baffles. Ports D are provided at alternate ends of each baffle row, so that the heating gases from the fireplace A first pass 55 below the lowest row of vessels C, then

through the port D at the end of that row into the space below the next row and so on to the chimney E. Thus the greatest heat is applied where it is most required, to the bases of those vessels containing the most 60 concentrated liquor, while thereafter the heat is mainly applied to the bases of the other vessels C (owing to the upward course of the gases) although the upper portions of all the vessels C are exposed to the hot 65 flue gases.

In some cases the vessels C in each row may touch one another without any packing, but where refractory packing is required it is preferred to use asbestos rope F 70 or the like. To enable this to be easily applied holes G are made in one or both of the side walls J of the flue B adjacent to those through which the vessels C extend. It will then only be necessary to insert and push or 75 draw the rope packing through the holes G, the diameter of the rope being such that the latter will rest in the space between adjacent vessels.

The baffle rows of vessels C may either 80 be arranged substantially horizontally as shown or they may slope upward from end to end, the end at which the port D is situated being the higher one of each baffle row.

The liquor to be concentrated is fed separately 85 to each of the vessels C in the topmost baffle row through funnels K, whence it flows to the corresponding vessel in the row below and so on until it is finally discharged from the vessels in the lowest row into a 90 common channel L. Thus there are a number of separate concentration apparatus equal to the number of vessels in each row being simultaneously operated.

The ends of the vessels C extend through 95 the side walls of the flue B as shown in Fig. 2 and an exit opening C¹ is provided in one end wall of each vessel. An inlet opening is formed at the other end of each vessel and the rows of vessels are alternately arranged 100 so that the inlets are situated below the exits of the vessels above them. A funnel C² extends from the inlet of each of the vessels in the rows below the topmost one up to the exit C¹ of the vessel immediately 105 above it. These funnels open below the exits of the upper vessels on the side adjacent thereto but on the opposite side they are extended above the exits, so that if ebullition 110 should cause a sudden acceleration in the

flow of the liquor the latter will be caught by this extended part of the funnel instead of being splashed on to the adjacent fittings.

Each of the vessels C is provided with a transverse weir or the like C³ disposed adjacent to its exit C¹ and governing the height of liquor in the vessel. The exit C¹ is below the level of the top of the weir C³ and has an opening at least as large as that above the weir. Outside the vessel the lower side of the exit is preferably sloped to a spout to prevent liquor from running along the exterior surface of the vessel. Inside the vessel this lower side of the exit is also preferably sloping as shown at C⁴, extending up to a line above the floor of the vessel but below the top level of the weir C³. Thus, if there should be a sudden surge of liquor over the weir C³ the space between the weir and the exit will tend to break its force and so prevent splashing outside the exit opening.

The vapors evolved during the concentration will be given off through the exits C¹ and the funnels C² and may be collected by providing additional side walls M. Doors N are provided in these side walls to enable the vessels C to be easily placed in position or renewed without dismantling the apparatus.

What we claim and desire to secure by Letters Patent is:—

1. In an evaporator, the combination of a flue, a plurality of series of pipe-like evaporating vessels extending across the flue, each series comprising a plurality of said vessels arranged side by side to constitute a baffle preventing direct upward movement of gases in the flue throughout the area of said series of vessels, means at one side of each series of vessels for conducting gases from the space below to the space above said vessels, said means being arranged alternately at opposite sides of the flue, and means for conducting liquor from each vessel in one series to the corresponding vessel in the next lower series, substantially as and for the purpose set forth.

2. In an evaporator, the combination of a flue, a plurality of series of pipe-like evapo-

rating vessels extending across the flue, each series comprising a plurality of said vessels arranged side by side, packing closing all of the spaces between the vessels in each series whereby each series of said vessels forms a baffle preventing direct vertical movement of the heating means through any part of the area of said series, means at one side of each series of vessels for conducting gases from the space below to the space above said vessels, said means being arranged alternately at opposite sides of the flue, and means for conducting liquor from each vessel in the upper series to a corresponding vessel in a lower series, substantially as and for the purpose set forth.

3. In an evaporator the combination of a flue, means for passing hot gases therethrough, pipe-like evaporating vessels extending across the flue, through its walls and disposed side by side in a plurality of rows to form preferably horizontal baffles for the flue gases, holes in the flue walls between adjacent vessels to enable asbestos rope packing to be applied between the vessels and means for causing liquor to flow from each vessel in one baffle row to a corresponding vessel in the row below, substantially as set forth.

4. In an evaporator a pipe vessel having a weir adjacent to one end limiting the height of liquor in the vessel and an exit in the weir end of the vessel having a larger opening than that above the weir and situated below the top level of the weir, substantially as set forth.

5. In an evaporator a pipe vessel having a weir adjacent to one end limiting the height of liquor in the vessel, an exit in the weir end of the vessel having a larger opening than that above the weir and situated below the top level of the weir, and a sloping lower side to the exit extending from the bottom thereof within the vessel to a line above its floor but below the top level of the weir substantially as set forth.

In testimony whereof we have signed our names to this specification.

JOHN HARRIS.

DAVID HIBBERT THOMAS.
